FRANCIS G. BATES AND FRANK H. BATES, OF PHILADELPHIA,
PENNSYLVANIA.

STEAM-BOILER.

SPECIFICATION forming part of Letters Patent No. 691,580, dated January 21, 1902.

Application filed November 9, 1896. Serial No. 611,457. (No model.)

To all whom it may concern:

Be it known that we, FRANCIS G. BATES and FRANK H. BATES, citizens of the United States, and residents of Philadelphia, in the county of Philadelphia and State of Pennsylvania, have jointly invented certain new and useful Improvements in Steam-Boilers, of which the following is a specification.

This invention relates generally to water-tube boilers, and particularly to upright water-tube boilers.

Figure 1 of the accompanying drawings is a front elevation of the preferred construction of our improved boiler. Fig. 2 is a horizontal section on the line 2 2 in Fig. 4. Fig. 3 is a horizontal section on the line 3 3 in Fig. 4. Fig. 4 is a vertical mid-section. Fig. 5 is a section of one of the upright water-tubes on a larger scale. Fig. 6 is a cross-section of Fig. 5 on the line 6 6. Fig. 7 is a fragmentary sectional plan showing the connections for introducing fuel-gas to the grate-bars. Fig. 8 is a transverse section through the grate-bars, showing the gas-passages therein.

The specific boiler shown in the drawings is designed, primarily, to be heated by combustion of fuel-gas, although it may be used for burning solid fuel. The boiler is of that general class wherein a steam-drum above and a mud-drum beneath are connected by water-tubes, the flames or hot gases being arranged to circulate around these tubes.

Let A designate the furnace, and B the grate thereof. The furnace A communicates with an upright chamber C, formed by masonry walls lined, preferably, with fire-brick. The steam-boiler proper is inclosed in the chamber C. The boiler is constructed with a steam-drum D, a mud-drum E, and boiler-tubes F F, extending between them and arranged concentrically, preferably in the manner shown in Fig. 3, where a central space is shown for the free upward circulation of hot gases after the same have passed around and between the tubes. The steam-drum D is formed with a tubular flue G, extending through its central portion and communicating with this space inclosed by the flues. From the flue G leads a flue G', which communicates with a stack or chimney.

The boiler is supported by brackets a a,

bolted to the steam-drum D and resting on a ledge formed in the upper portion of the masonry shell C of the furnace. The mud-drum E is suspended from the steam-drum through the intervention of the tubes F, so that expansion or contraction of the tubes is allowed for by a slight rise or fall of the mud-drum. To permit of access being had to the tubes, the steam-drum D is made in two portions divided horizontally, the upper portion or cap (lettered D') being removable. It is connected to the lower portion by means of flanges b and c, riveted to the outer shell and to the tube forming the flue G, respectively. For reaching these inner flanges in order to tighten the bolts connecting them a manhole d, Fig. 2, is provided, which is reached through a door e, closing an opening in the outer masonry. The upper portion of the steam-drum projects into a chamber C', formed within the masonry C and covered by a cap H, which may or may not be cast integrally with the flue G'. The cap H may be removed, taking the flue G' with it, to gain access to the chamber C'. For taking off the cap D' the bolts of the outer flanges b are accessible from this chamber.

The feed-pipe I enters laterally into the lower portion of the steam-drum beneath the water-line and preferably curves around therein, as shown in Fig. 2. The steam-pipes J J (one or more) lead, preferably, from the cap D' of the steam-drum, as shown. As the circulation in the water-tubes F is upward, a downflow-pipe K is provided, extending, preferably, exterior to the masonry wall C, for taking the water from one side of the steam-drum D and delivering it into the mud-drum E. A blow-off pipe L is provided, leading from the bottom of the mud-drum and normally closed by a valve f. For cleaning the mud-drum a manhole d is provided in its bottom, closed in the usual way.

A water-column M and water gage or tube N are arranged outside the masonry and connected by horizontal tubes to the drum D, these tubes being arranged, respectively, above and below the extreme variations of water-level. The water-column M has gage-cocks, as usual, for determining the water-level.

The flames from the fuel in furnace A pass

over the bridge and into the upright chamber containing the tubes F, and the flames and hot gases circulate around these tubes, heating the water therein, the hot products 5 of combustion finally escaping by the flues G G' to the stack. The water in the tubes is heated and circulates upwardly, the cooler water in the drum above flowing downward by the pipe K to the lower drum, whereby a 10 circulation is maintained.

For burning fuel-gas in the furnace the grate B is made up of bars which are cast with gas-passages traversing them longitudinally, as shown in transverse section in Fig. 8. 15 Small holes are drilled at intervals through the top of each bar, communicating with these passages, so that the gas may issue from these holes and be ignited above the grate-bars. The gas enters through a pipe 20 P into a transverse pipe or header h, as shown in Fig. 7, and from this through branch pipes i i to the grate-bars. The pipes i are made in two sections united by couplings j to admit of disconnecting any grate-bar independently of the other. The supply of air for maintaining combustion can be introduced through dampers in doors k k, which open beneath the grate into the ash pit or chamber l. Air may also be admitted through 25 a damper in a door m, communicating with the combustion chamber or space above the grate. In a furnace burning solid fuel the door m becomes the charging-door and the doors k k the ash-doors. Air may be admitted in admixture with the gas, if desired, as in any ordinary Bunsen burner.

An important feature of our invention is shown best in Figs. 5 and 6. These figures show one of the water-tubes F, having suspended within it a heat-retaining core Q. This core is extended longitudinally of the tube for preferably its entire length and is arranged concentrically within it, so that the water in the tube is divided into an annular 40 or tubular column, the center of which is occupied by the core Q. It results that the layer of water coming against the wall of the tube is reduced in thickness to an extent varying according to the greater or less diameter of 45 the core Q in proportion to the diameter of the water-tube. By relatively increasing the diameter of the core the water may be reduced to a comparatively thin stratum or layer. The result is that the water is more 50 rapidly heated than if the core were absent, so that the boiler has a greatly-increased capacity for quickly generating steam. Another important function of the core lies in its capacity for absorbing and storing heat. 55 To this end we make the core of a heat-absorbent material, preferably constructing it of a somewhat thin metal tube filled with any suitable heat-retaining material, preferably a mortar of lime and sand. The cores arranged 60 in the numerous boiler-tubes have thus a considerable aggregated heat-storing capacity. The practical effect of the use of 65

such heat-retaining cores is to equalize the heating effect upon the columns of water, since whenever the exterior source of heat is discontinued or reduced, so that the water tends to cool, the cores commence giving out heat to the water, so that they keep up the temperature of the water for a time above what it would otherwise be, and hence the 70 steam-generating action of the boiler continues with greater uniformity under variations in the source of heat than would be the case in a boiler of ordinary construction. This is especially desirable in boilers heated by gas 75 derived from local fuel-gas plants, since at times it becomes necessary to wholly or partially suspend the introduction of gas for a few minutes, and in such case the steam-pressure is maintained with less diminution than 80 would be the case if the heat-retaining cores were not used. This feature of our invention is applicable in connection with any construction of water-tube boiler, whether the tubes extend vertically or otherwise, but is most 85 effective in connection with upright tubes or inclined tubes which approximate to an upright arrangement.

For supporting the cores and holding them concentrically each core is provided with a 90 spider p, screwed or fastened on its upper end, and having, preferably, three arms which extend downwardly, overlying the upper end of the tube F and also extending down within it for a short distance, as clearly shown in 95 Fig. 5. Another spider q is arranged for holding the lower end of the tube concentric, this spider, however, consisting merely of arms projecting outwardly and lying loosely against the inner walls of the tube. These 100 spiders may form caps for closing the outer ends of the tube, as with the construction of spider q shown, or a separate cap may be applied exterior to the spider, as is shown at r. 105

What we claim is—

1. A water-tube boiler having its tubes provided with heat-absorbent cores arranged within them and means for holding the cores separated from the tubes so as to leave an annular space between the tube and core for 110 circulation of water, such cores constructed as tubes inclosing a heat-absorbent material.

2. A water-tube boiler having its tubes provided with heat-absorbent cores within them, said cores constructed as a sealed metal tube 115 with a filling of heat-retaining mortar.

3. In a boiler, a vertical water-tube combined with a concentric core-tube within it, having a centering spider at its bottom engaging the inner surface of the water-tube, 120 and having at its top a suspending-spider having arms overlying and projecting within the water-tube to support and center the core-tube, all adapted to permit the core to be drawn out upwardly.

4. An upright tubular boiler comprising an annular steam-drum D, a mud-drum E, and intervening tubes F F, an upright chamber inclosing the tubes, a furnace commu- 125 130

nicating with the bottom of said chamber, a flue through said annular drum, and a down-flow-pipe K exterior to said chamber leading from the steam-drum below the water-level 5 to the mud-drum.

5. A boiler comprising a steam-drum D, mud-drum E, and intervening upright water-tubes F F, the steam-drum constructed with a concentric flue G within it, and formed in 10 two parts divided horizontally, and provided with flanges b c for uniting them, and with a manhole d for giving access to the interior of the steam-drum.

6. In a steam-boiler, the combination of an 15 upright chamber C communicating at its lower portion with a furnace A, a steam-drum D

supported upon the wall of said chamber, water-tubes F F, and mud-drum E, suspended from said steam-drum, cap H covering the top of said wall and forming a chamber C' 20 inclosing the upper portion of the steam-drum, and flues G and G' formed respectively through said steam-drum and chamber C'.

In testimony whereof we have hereunto signed our names in the presence of two sub- 25 scribing witnesses.
